HOLDING DEVICE FOR METAL TRIMS

Filed Oct. 16, 1939.

FIG. 1.

FIG. 4.

FIG. 5.

FIG. 7.

Inventor:
Charles D. Schroeder,

F. G. Fisher,

Attorney.

UNITED STATES PATENT OFFICE

2,218,832

HOLDING DEVICE FOR METAL TRIMS

Charles D. Schroeder, Kansas City, Kans.

Application October 16, 1939, Serial No. 299,713

2 Claims. (Cl. 24—73)

My invention relates to holding device for moldings such as are used as ornamental trims in architectural, industrial and home decorations, and the present invention relates more particularly to holding means whereby the moldings may be quickly and reliably attached to various supporting structures, such, for instance, as walls, counters, furniture, store fixtures, automobiles, cabinets, etc., without driving nails through the moldings and thereby disfiguring their exposed surfaces which are usually highly polished.

The moldings usually comprise strips of stainless steel, chromium, brass, bronze, copper, plastics or other suitable materials and said moldings may be of various cross sectional configurations with flanges along their longitudinal margins for engagement with the holding means to secure the moldings firmly but removably in applied position.

The holding means consist of devices made of resilient material such, for instance, as lengths of wire of suitable gage bent into suitable forms so that the devices may be secured in place with appropriate fastening means such as nails or screws which together with said devices are concealed by the molding strips when the same are in applied position.

In order that the invention may be fully understood, reference will now be had to the accompanying drawing, in which:

Fig. 1 shows a plurality of the holding devices secured to a wall with a broken portion of a molding strip applied to one of the devices.

Fig. 2 is an enlarged front elevation of one of the holding devices shown by Fig. 1.

Fig. 3 shows an end elevation of one of the holding devices secured to the wall and a molding strip in cross section and being applied to the device.

Fig. 4 is a view similar to Fig. 3 with the molding strip in applied position.

Fig. 5 shows an end elevation of one of the holding devices bent at right angles and secured to the corner of a supporting structure and supporting a molding strip bent at right angles.

Figs. 6 and 7 show modified forms of the device.

In the present instance I have shown a molding strip A of convex cross section and another of right angle cross section with confronting flanges B and C along the longitudinal margins of the body portion of the strips for engagement with the lower and upper portions of the holding devices indicated generally by the numeral 2. When applied to a supporting structure such as the

wall D, Fig. 1, the devices 2 are arranged with their upper portions 3 in horizontal alignment and each device is preferably secured to the wall with a nail or screw E.

My preferred form of holding device consists of a length of resilient wire bent at its upper portion into a loop 4 of triangular shape and terminating at its lower portion in the form of a pair of downwardly diverging arms 6, the upper portions of which are crossed and bent to provide an opening 8 to receive a nail or screw E whereby the device may be firmly secured to the wall. The lower free ends of the arms 6 are bent upwardly as indicated at 10 so that the molding strips A may be slid longitudinally upon or off of the holding devices 2 without the ends of the strips impinging against the terminals 12 of the arms.

However, each strip A is preferably applied to the holding devices 2 by engaging the flange B with the underside of the bent portions 10 of the arms 6 and then forcing the strip upward and engaging the flange C over the upper portion 3 of the devices. When the strip A is forced upward as stated the flange B pushes the arms 6 upward as indicated by dotted lines, Fig. 2, so that the flange C may be easily engaged over the upper portion 3 of the holding devices without expanding the strip A as is necessary when it is applied to holding means such, for instance, as a track secured to the wall. After the flange C has been engaged over the upper portion 3 of the holding devices the arms 6 spring downward towards their normal position. During the foregoing operations the flanges B and C are forced between the rear surface of the holding devices 2 and the front surface of the wall and thus cooperate with the devices in firmly holding the strip A in applied position, although it may be manually removed by sliding the strip longitudinally off of the devices, or by pushing the strip upward and disengaging the flange C from the devices and then lowering the strip to disengage the flange B.

The holding devices 2 secure the molding strips A so firmly that said strips may be arranged vertically, or at any desired inclination as well as in a horizontal position as shown, without becoming accidentally disengaged from the holding devices.

The modified form of holding device 2a disclosed by Fig. 6 comprises a length of resilient wire bent somewhat in the form of an ellipse having an arched upper portion 2a bent downward at its ends 18 and terminating in a pair

- of arms $6a$ which extend towards each other and have their lower portions bent upwardly as indicated at $10a$, so that their ends $12a$, which are spaced a short distance apart will not be in the way when a molding strip is being slid longitudinally upon or off of the holding devices, or the strip may be applied in the same way as when applied to the devices 2 . This form of holding device may be secured to a supporting structure with two nails placed just inside the ends 15 of the device so that when the nails are driven into the supporting structure their heads will overlap the portion $3a$ and arms $6a$ and thus firmly hold the device in place.
- 15 The modified form of holding device $2b$ shown by Fig. 7 is similar to the form disclosed by Fig. 6, as is evident by like reference numerals with exponents b , with the exception that the ends are formed into coils 16 to provide openings $8b$ through which nails may be driven into the supporting structure.
- 20 From the foregoing description taken in connection with the drawing it is evident that I have provided holding devices which are well adapted

for the purpose intended, and while I have shown and described several forms of holding devices I reserve all rights to such other forms and modifications thereof as properly fall within the spirit and scope of the invention as claimed.

Having thus described my invention, what I claim and desire to secure by Letters Patent, is:

1. A holding device of the character described formed from a length of resilient material and comprising a looped portion and a pair of arms integral with the ends of said looped portion and which diverge towards their free ends, the adjacent portions of said arms being crossed and bent to provide an aperture.

2. A holding device of the character described comprising a looped portion and a pair of arms integral with the ends of said looped portion and having their free ends bent in reverse directions to each other, the adjacent portions of said arms being crossed and bent to provide an aperture, and fastening means adapted to extend through said aperture and secure the holding device to a supporting structure.

CHARLES D. SCHROEDER.
